CLAIM

We claim the ornamental design for a portable electronic device case, as shown and described.

DESCRIPTION

FIG. 1 is a rear perspective view of a portable electronic device case according to the present invention;

FIG. 2 is a rear plan view of the portable electronic device case shown in FIG. 1.

FIG. 3 is a front plan view of the portable electronic device case shown in FIG. 1.

FIG. 4 is a first side view of the portable electronic device case shown in FIG. 1.

FIG. 5 is a second side view of the portable electronic device case shown in FIG. 1.

FIG. 6 is a top view of the portable electronic device case shown in FIG. 1; and,

FIG. 7 is a bottom view of the portable electronic device case shown in FIG. 1.

Portions of the electronic device case shown in broken lines form no part of the claimed design.
